WINDOW DEVICE

Bert N. Parmenter, Lake Forest, Ill.

Application May 6, 1935, Serial No. 20,013

12 Claims. (Cl. 296—44)

The present invention relates to window devices, and more particularly to the deflecting type of window, such as those used in vehicles, although the invention is not limited to windows in vehicles but is equally applicable to windows in stationary structures, such as buildings, the invention being herein disclosed in connection with an automobile for the purpose of illustration.

Among the objects of the invention is to provide a novel window device having a pane which may swing on an oblique axis to cause movement of air over, by or past the upper and forward portions of the pane and also under, by or past the lower and rear portions of the pane.

Another object of the invention is to provide a novel window construction as above mentioned with novel friction means for normally holding the pane in any of its moved positions.

A further object of the invention is to provide a novel window device as above mentioned with novel bearings so arranged and constructed as to movably support the pane for movement about an oblique axis.

Another object of the invention is to provide a novel window device as above mentioned with novel bearings having novel friction means, preferably adjustable, so arranged and constructed as to controllably hold the pane in any of its moved positions.

Another object of the invention is to provide a novel window device having a pane which will swing about an oblique axis to deflect air as above mentioned and having means, such as a frame, so arranged and constructed as to slide, at will, into the supporting means for the frame, with or without means for slidably moving the frame.

Other objects, advantages, capabilities, features and the like are comprehended by the invention as will later appear and as are inherently possessed thereby.

Referring to the drawings:

Fig. 1 is a side elevational view with parts shown broken away of an embodiment of the invention in a vehicle;

Fig. 2 is a fragmentary elevational view of part of the device shown in Fig. 1;

Fig. 3 is a view similar to Fig. 1 but showing the pane in open or partly open position;

Fig. 4 is a sectional view taken in a plane represented by line 4—4 in Fig. 1 of the drawings;

Fig. 5 is a sectional view taken in a plane represented by line 5—5 in Fig. 3 of the drawings;

Fig. 6 is a fragmentary sectional view taken in a plane represented by line 6—6 in Fig. 1 of the drawings;

Fig. 7 is a sectional view taken in a plane represented by line 7—7 in Fig. 1 of the drawings and showing one of the bearings;

Fig. 8 is a sectional view taken in a plane represented by line 8—8 in Fig. 7 of the drawings;

Fig. 9 is a vertical sectional view of a connecting link means between the frame and pane and the friction bearing therefor;

Fig. 10 is an elevational view of the linkage;

Fig. 11 is a sectional view of an alternate form of bearing;

Fig. 12 is a sectional view of another alternate form of bearing; and,

Fig. 13 is a sectional view taken in a plane represented by line 13—13 in Fig. 12 of the drawings.

Referring to the drawings, the embodiment selected to illustrate the invention is shown in connection with an automobile or like vehicle having a body 1 having a side opening normally closed by a door 2 suitably supported by hinges 3 connected to the front 4 of the vehicle. The door comprises a hollow lower portion or casing 5 (Figs. 4 and 5) in which is located the operating mechanism 6 for opening and closing the window of the door, such mechanism including a lever 7 and a trunnion 8 operating in a slot 9 in the lower part of the window frame 10, for raising and lowering the frame 10 and the window carried by it. In the upper part of the door is provided a window opening 11, a lintel 12, forward post 13, rear post 14, and a ledge 15.

The window frame 10 is in the general form of an H, and comprises upright limbs 16 and 17 and a cross piece 18. The vertical limbs 16 and 17 slide vertically in channels provided respectively in the posts 13 and 14. It will be noted that the limb 16 is short and has an upper portion 19 and a lower portion 20, while the limb 17 is long and has an upper portion 21 and a lower portion 22. The limb part 21 extends nearly the full height of the window to the upper rear corner thereof while the limb part 19 extends only to the lower forward corner of the window.

In the opening 11 is located a pane 23 the upper and forward edge portions 24 and 25 of which, when in closed position, laterally abut packing 26 on the inside of the weather strip 27 (Figs. 4 and 5). The lower and rear edge portions 28 and 29 of the pane are seated in the channels of a sash 30 having a rear portion 31, a bottom or lower portion 32 and a short forward portion 33. These portions are adapted, when the pane is in closed position, to laterally abut the packing 34 secured to the stop or weather strip 35 on the frame 10. The glass 55

pane is set in the channel of the sash with a suitable material such as an adhesive or cementitious substance 36.

The pane 23 and its sash 30 are supported to swing about an oblique axis 37, the upper rear part and the lower forward part of the pane having frictional bearings 38 and 39 shown more in detail in Figs. 7, or 11 or 12. Both the upper and lower bearings are alike.

10 In the form of bearing shown in Fig. 7, the device comprises a coupling having a non-circular socket 40 (shown as square in the illustrative embodiment) rigidly secured to the periphery of the sash portion 31 at the upper end thereof (see Fig. 1), and a shaft 41 having a non-circular part 42 (also square) fitting into the socket 40, and a conical friction part 43. The parts 40 and 42 may slide axially in compensation for any variation in fit of the parts, 20 but will rotate together. The socket 40 is exteriorly round and is rotatably supported in an opening formed in the inner wall 44 of the frame part 21. In the frame part 21 is located a spider 45 in which is secured a tube or housing 46 in which the shaft 41 extends. This tube or housing has a conical part 47 between which and the cone part 43 of the shaft is interposed a friction member 48 of any suitable material. In the tube 46 is a spring 49 normally acting 30 against a washer 50 pressed against the shoulder 51 of the tube member 46, the other end of the spring reacting against a washer 52 bearing against the nut 53 on the threaded end 54 of the shaft 41. By turning the nut 53 the force of 35 the spring 49 may be varied to adjust the friction between the friction member 48 and the cone part 43 of the shaft. The socket 40 may have laterally extending legs 55 rigidly secured or fastened with the peripheral part of the upper end portion of the sash part 21 (Fig. 1).

When the pane 23 and its sash are swung about the oblique axis 37 the sockets 40 turn in the openings in the walls 44 and cause a turning of the shafts 41 by way of the non-circular (square in the illustrative embodiment) coupling parts 40 and 42. The cone parts 43 of the shaft are so frictionally engaged with the friction members 48, which in turn are frictionally engaged with the cone parts 47 of the tubes or 45 housings 46, as to turn when the pane is moved about its axis and to normally hold the pane in any of its moved positions.

The bearings may be of the form shown in Fig. 11 wherein the socket 40 extends through a bearing aperture in the wall 44^a of the upper part 21^a and is coupled to the squared portion 42^a of shaft 41^a. To the end of the shaft 41^a is a ball or sphere 56 held in frictional engagement between cup shaped friction members 57 and 58 of any suitable material and held in cup shaped bearings 59 and 60 of which the latter has a flange 61 secured as by rivets 62 to the frame part 21^a, while the part 59 is movable and carried by a spring 63 connected to 60 a plate 64 carried by an adjusting screw 65 mounted in the bracket 66 having a flange 67 secured as by rivets 68 to the frame part 21^a. A lock nut 69 locks the screw 65 in adjusted position. By adjusting the screw 65, the friction on the ball 56 may be varied at will.

When the pane is moved about its oblique axis 37, the socket 40 turns the parts 42^a, 41^a, and 56, the latter having such a frictional engagement with the friction members 57 and 58 as

to permit such a movement and yet normally hold the pane in any of its moved positions.

In Fig. 12 is shown a further form of bearing of the multiple disc type. In this case the socket 40^b is preferably reversed so as to extend into the sash part 31^a, the pane 23 being cut away to clear the socket 40^b. This socket has legs 55^a rigid with the peripheral part of the sash part 31^a as shown in Fig. 12. In the inner wall part 44^b of the frame part 21^b is provided an opening in 10 which is fixed the inner end of a casing 70 this casing being square or non-circular in cross-section. The outer end of the casing is located opposite an opening 71 provided in the upper corner of the door 2^a, this opening being normally 15 closed by a plate 73 secured as by screws 74 to the door 2^a. The outer end portion 75 of the casing 70 is round and threaded to receive a cap 76 as shown in Fig. 12. In the casing 70 is a housing 77 of the same cross-sectional shape as the casing 70 and slidably fitting therein. The housing 77 has a flange 78 having a circular opening 79 for the passage therethrough of a shaft 80 preferably of polygonal cross-section, such as square, the opening 79 being of a size to permit 25 free rotation of the shaft 80 therein. The inner end of the shaft 80 has a coupling part 81 of polygonal shape such as square to slidably fit in the socket 40^b so that axial movement may be attained in compensation for variations in fit and 30 manufacture of the device. The part 81 has a circular collar 82 between which and the flange 78 is located a friction member 83 having a square perimeter fitting in the housing 77 and having a circular hole for the rotation of the shaft 80 35 therein. On the outer side of the flange 78 are a plurality of like friction members 83 having square peripheries or perimeters to fit in the housing 77 and circular holes for the rotation of the shaft 80 therein, and alternating therewith are a plurality of discs 84 of suitable material and having square holes for fitting with the squared part of the shaft 80 and having circular peripheries for rotating in the housing 77. A spring 85 normally presses these parts together to 45 effect the given or desired frictional resistance, the spring 85 reacting against a washer 86 backed by an adjusting nut 87 on the threaded end 88 of the shaft 80. The nut 87 may be located in a socket 89 provided in the cap 76.

When assembling the friction device is inserted through the hole 71 into the casing 70 with the flange 82 abutting the shoulder 90 of the socket 40^b, and the cap 76 is screwed into place to abut the outer end of the housing 77 to hold the parts 55 in place. The nut 87 is adjusted to the desired degree to give the required friction among the discs 84 and members 83. The plate 73 is then attached in place. When the pane is moved about the oblique axis 37 the socket 40^b turns with the 60 coupling part 81, shaft 80 and discs 84, the latter having frictional engagement with the friction members 83 held from turning in the housing 77. The friction is such as to permit such movement of the pane but to hold the pane in any of its 65 moved positions.

In order not to depend entirely on the friction of the bearings to hold the pane in any of its positions, additional friction means may be used such as a link 91 having a slot 92 in which 70 rides a pin 93 fixed to the sash part 31 (Fig. 10). The end 94 of the slot is enlarged or of such a size as to permit passage of the head of the pin 93 when assembling.

The upper end of the link 91 is connected to 75

friction means shown in detail in Fig. 9. This means may comprise a shaft 95 having a friction conical part 96 and a squared or polygonal part 97 fitting in a socket 98 rigid or integral with the 5 link or arm 91. In the frame 17 is located a spider 99 carrying a shell 100 having a conical part 101 between which and the conical part 96 of the shaft is located a conical friction member 102 of suitable material. In the shell 100 is a 10 spring 103 acting against a washer 104 seated against the shoulder 105 formed in the shell 100, the spring 103 reacting against a washer 106 abutting an adjusting nut 107 threaded upon the threaded end portion 108 of the shaft 95. The 15 spring 103 normally acts to effect frictional engagement between the friction member 103 and the conical parts 96 and 101.

When the pane is moved about its axis, the link 91 is swung so that as the socket 98 turns it also turns the coupling part 97 and the shaft 95. The friction between the friction members 102 and the conical parts 96 and 101 is such as to permit forcible movement of the pane but to hold the pane in any of its moved positions against any component of force effected by the wind or air acting upon the outside surface of the pane.

To manually move the pane the sash part 32 has connected thereto a finger ring 109 having journals 110 rotatable in a bearing 111 fixed to a projection 112 rigid or integral with the sash part 32. To normally hold the ring 109 parallel to the pane when the latter is raised from or lowered into the lower casing 5 of the door 2, a 5 spring 113 is provided with an end 114 thereof secured to the projection 112 and the other end 115 thereof passing through a slot 116 formed in the bearing 111 and secured to the journals 110. When the ring 109 is swung to the dotted line 10 position thereof shown in Fig. 6, the spring 113 will swing it back to the full line position thereof when the ring 109 is released by the operator of the pane.

The ledge 15 has a slot through which the frame 10 and the pane 23 when in closed position may be lowered to or raised from the hollow casing 5 of the door 2. Should the ring 109 extend laterally when the frame 10 and pane 23 are being lowered, the hitting of the ring 109 against the top of the ledge 15 will automatically cause the ring 109 to swing upward and be held in parallelism with the pane by the spring 113.

When the pane 23 is in open or partly open position (see Figs. 3 and 5) the air hitting the 55 pane will be deflected and will cause movement of air through the openings provided at the upper and forward portions of the pane and at the lower and rear portions of the pane. The pane in such position also sheds rain and the like and prevents 60 entry of the same in the tonneau. Another advantage is that when the pane is open as shown for example in Figs. 3 and 5, the rider may easily 65 extend his hand or arm outwardly to effect signals through the opening between the lower part of the pane and the ledge of the door.

Having thus disclosed the invention it is to be understood that the same is not limited to the particular construction described in the specification and shown upon the drawings but comprehends other constructions, details, arrangements of parts, features and the like, without departing 70 from the spirit of the invention.

Having thus disclosed the invention, I claim:

1. A window construction comprising a pane 75 and bearings so arranged and constructed as to

support the pane for movement about a diagonal axis whereby the top and front portions of the pane may swing inwardly and the bottom and rear portions of the pane may swing outwardly for flow of air over and past the former portions and also under and past the latter portions.

2. A window construction comprising a movable frame, a pane adapted to fit in said frame when in closed position, bearings in said frame and being so located and constructed and so connected to said pane as to movably support said pane for movement about an oblique axis whereby the forward and upper portions of the pane swing inwardly and the rear and lower portions of the pane swing outwardly for flow of air by 15 and past the former portions and also by and past the latter portions.

3. A window construction comprising a movable frame, a pane adapted to fit in said frame when in closed position, bearings in said frame 20 and being so located and constructed and so connected to said pane as to movably support said pane for movement about an oblique axis whereby the forward and upper portions of the pane swing inwardly and the rear and lower portions of the pane swing outwardly for flow of air by 25 and past the former portions and by and past the latter portions, and friction means for normally holding the pane in any of its moved 30 positions.

4. A window construction comprising a movable frame, a pane adapted to fit in said frame when in closed position, bearings in said frame and being so located and constructed and so connected to said pane as to movably support said pane for movement about a diagonal axis whereby the forward and upper portions of the pane swing inwardly and the rear and lower portions of the pane swing outwardly for flow of air by 40 and past the former portions and also by and past the latter portions, and means connected to said pane and to said frame and having friction elements for normally holding the pane in any of its moved positions.

5. A window construction comprising a frame, a pane adapted to fit in said frame when in closed position, bearings in said frame and being so located and constructed and so connected to said pane as to movably support said pane for movement about an oblique axis whereby the forward and upper portions of the pane swing inwardly and the rear and lower portions of the pane swing outwardly for flow of air by 45 and past the former portions and also by and past the latter portions, said bearings each having a 50 coupling connected to said frame and to said pane and the elements of which are axially relatively movable and angularly fixed.

6. A window construction comprising a movable frame, a pane adapted to fit in said frame 60 when in closed position, bearings in said frame and being so located and constructed and so connected to said pane as to movably support said pane for movement about a diagonal axis whereby the forward and upper portions of the pane swing inwardly and the rear and lower portions of the pane swing outwardly for flow of air by 65 and past the former portions and also by and past the latter portions, said bearings each having a coupling an element of which is connected to said pane and another element of which is connected to said frame, said elements being so arranged and constructed as to have relative axial movement and to be angularly fixed.

7. A window construction comprising a frame, a single full size pane adapted to fit in said frame when in closed position, bearings in said frame and being so located and constructed and 5 so connected to said pane as to movably support said pane for movement about an oblique axis whereby the forward and upper portions of the pane swing inwardly and the rear and lower portions of the pane swing outwardly for flow of 10 air by and past the former portions and also by and past the latter portions, said frame being so arranged and constructed as to slide in the supporting means for the frame, and means for slidably moving said frame.
- 15 8. A window construction comprising a wall having a window opening therein, a frame vertically adjustable from a position within the opening to a position outside thereof and a window pivotally mounted in the frame on a diagonal 20 axis extending between the lower front and upper rear corners of said frame.
9. In a vehicle body having a window opening therein, a window located within said opening, and rotative supporting means for said window 25 mounted on an approximately longitudinally disposed axis arranged diagonally with respect to said opening and so constructed and arranged that the top and front portions of the window may swing inwardly and the bottom and rear 30 portions of the window may swing outwardly.
10. In a vehicle body having a window opening therein, a window, and means for supporting the window within said opening, said means including a pair of relatively spaced pivots arranged 35 one higher than the other and having a common approximately longitudinally disposed axis of rotation arranged diagonally with respect to the
- window opening, the higher pivot being located rearwardly with respect to the lower pivot, said pivots being so constructed and arranged that the top and front portions of the window may swing inwardly and the bottom and rear portions 5 of the window may swing outwardly.
11. In a vehicle body having an opening therein, a vertically adjustable window frame having a window opening therein positioned to register with the first mentioned opening, a window located in said window opening, and rotative means for supporting said window, said supporting means being disposed on an axis approximately longitudinally arranged diagonally with respect to the opening in said frame and so constructed 15 and arranged that the top and front portions of the window may swing inwardly and the bottom and rear portions of the window may swing outwardly.
12. In a vehicle body having an opening therein, a vertically adjustable window frame having a window opening therein positioned to register with the first mentioned opening, a window, and means for supporting the window within said window opening, said means including a pair of relatively spaced pivots arranged one higher than the other and having a common approximately longitudinally disposed axis of rotation arranged diagonally with respect to the window opening, 20 the higher pivot being located rearwardly with respect to the lower pivot, said pivots being so constructed and arranged that the top and front portions of the window may swing inwardly and the bottom and rear portions of the window may swing outwardly.
- 30

BERT N. PARMENTER.
